UNITED STATES PATENT OFFICE.

AXEL LEVEDAHL, OF AURORA, ILLINOIS, ASSIGNOR TO INDEPENDENT PNEUMATIC TOOL COMPANY, OF CHICAGO, ILLINOIS, A CORPORATION OF DELAWARE.

CHISEL RETAINER FOR RIVETING HAMMERS.

Application filed February 10, 1922. Serial No. 535,624.

This invention relates to chisel retainers for pneumatic tools and more particularly for riveting hammers so that chisels may be applied to the latter for cutting off rivet heads in the removal of rivets in repair and other work.

One object of my invention is to provide a retainer permitting limited longitudinal movement of the chisel with respect to the sleeve in which the chisel is inserted so that the blows of the hammer piston on the chisel will have their full effect in the cutting operation of the tool and will not be fully absorbed in the parts of the retainer or the barrel of the tool to impair the cutting operation of the latter as heretofore.

Another object is to provide a retainer which will hold a relatively light chisel and thus permit the ordinary type of pneumatic riveting hammer being efficiently employed for cutting off the heads of rivets.

A further object of my invention is to retard or break the outward movement of the chisel at a point in such movement, not only to hold the chisel from dropping out of the barrel of the tool when the latter is idle, but to prevent the chisel and its holding sleeve from being shot out of the barrel by the hammer piston, either when the tool is operated before the chisel is placed against the work or when the chisel glances off a rivet while being cut and when the rivet head breaks off.

The invention consists further in the matters hereinafter described and more particularly set forth in the appended claims.

In the accompanying drawings—

Fig. 1 is a side elevational view of a pneumatic riveting hammer having attached to the forward end of the barrel thereof a chisel retainer of my invention;

Fig. 2 is an enlarged fragmentary longitudinal vertical sectional view through the forward end of the barrel and attached chisel retainer;

Fig. 3 is a transverse vertical sectional view taken on line 3—3 of Fig. 2;

Fig. 4 is an elevational view of one of the plugs used in the retainer structure, and

Fig. 5 is a transverse sectional view on line 5—5 of Fig. 2; and

Fig. 6 is an end view of the barrel, the re-

tainer being omitted for the sake of illustration.

In the drawings, 1 indicates the barrel of a pneumatic riveting hammer of the type handled by one man in setting rivets in steel structures. Attached to the forward end of said barrel is a chisel retainer of my invention, so that a chisel 2 may be applied to said riveting hammer and permit use of the latter for cutting off the heads of rivets in repair or other work.

Surrounding the forward end of said barrel 1 is a retainer sleeve 3 made in one piece and held on the barrel by two dogs 4, 4, preferably diametrically opposed and fastened as by rivets *a*, *a* to a spring clip 5 on the outside of said sleeve 3. Said dogs 4, 4 have inwardly extending prongs 6, 6 which extend into grooves 7 in the barrel 1 through slots 3^a, 3^a in the sleeve 3, as shown in Figs. 2 and 5. The inner ends of the prongs 6, 6 are rounded and the grooves 7, 7 are made concave on the same curvature, so that by turning the sleeve 3, the prongs will ride out of the grooves 7 on to the outer surface of the barrel between the grooves, whereupon the sleeve 3 and its spring clip 5 and prongs 6 as a complete assembly may be pulled off over the end of the barrel. The spring clip 5, which was expanded by the prongs riding out of the grooves, contracts against the sleeve 3 and holds the prongs projecting into the same, when the sleeve is off the barrel.

The end of the barrel is milled on opposite sides, preferably mid-way between the grooves 7 to provide flat inclined surfaces 8, 8, as shown in Fig. 6. In replacing the sleeve 3 on the barrel, the sleeve is first positioned with the prongs 6 of the dogs at the inclines 8 and is then pushed inward over the barrel until the prongs 6 come into the planes of the grooves, whereupon the sleeve is turned to carry the prongs to the grooves, the expanded spring clip 5 snapping the prongs into the grooves to fasten the sleeve 3 on the barrel, as is apparent.

As shown in Fig. 2, the sleeve 3 extends forward beyond the end of the barrel 1 to provide a space between such parts. Inserted in the forward end of the barrel is a metal sleeve 9 preferably made of steel and fitting the end or nozzle of the barrel. This

sleeve 9 projects into the space between the end of the barrel and the forward end of the sleeve 3, which there is provided with an inwardly extending flange 10, as shown in Fig. 2. Said sleeve 9 is provided beyond the end of the barrel 1 with an outwardly extending annular flange 11, and between the same and the flange 10 of the sleeve 3 is cushion means 12, such as soft flexible material, as for instance rubber.

The sleeve 9 is provided with a tapered passage or bore to receive the tapered shank 13 of the chisel 2. The shank 13 extends beyond the inner end of the sleeve 9 to receive the blows of the hammer piston (not shown) during the operation of the tool. The chisel shank 13 is provided with two diametrically opposed grooves 14, 14. These extend longitudinally of the shank 13 and are substantially parallel to each other and to the longitudinal axis of the chisel. Said grooves 14, 14 are made concave or rounded in cross-section and have a length less than that of the sleeve 9, as shown in Fig. 2. In to these grooves 14, 14 extend plugs 15, 15 carried by the sleeve 9 and having their inner ends rounded to conform to the shape of the grooves 14. Said plugs 15, 15 fit in holes or recesses in the sleeve 9, as shown. The outer ends of the plugs 15 are rounded off on a radius equal approximately to the bore of the nozzle 1 and engage the same. The plugs being thus made are slightly below the surface of the sleeve on opposite sides, as indicated at 16, 16, in Fig. 2. This metal is set over slightly and prevents the plugs from dropping out of the holes in the sleeve 9.

In assembling the parts, the chisel shank 13 is first inserted into the sleeve 9 while both of such parts are outside of the barrel 1 and the metal of the sleeve set over to hold the plugs in place, as described. Then the assembled parts are inserted into the barrel 1 and the retainer sleeve 3 applied with the packing 12 in place, as shown.

The inner end of the chisel shank 13 extending beyond the inner end of the sleeve 9 receives the blows of the hammer piston in the operation of the tool and drives the chisel forward with force against the work. The grooves 14, 14 permit a limited longitudinal movement of the chisel shank 13 in the sleeve 9 and thus allows the blows on the chisel to have full effect in the cutting operation without being absorbed by either the barrel 1 or the sleeve 9 to impair the force of these blows. The grooves 14, 14 have their ends inclined outward, as shown, and when these ends approach the plugs 15 as the chisel is driven forward, the plugs exert a wedging effect on the chisel shank to retard its outward movement. The plugs bearing against the bore of the barrel 1 are held from movement out of the grooves 14,

and thus the outward movement of the chisel after the full effect of the blow thereon has been utilized is gradually retarded like applying a brake to prevent shooting the chisel out of the sleeve 9. When this wedging action takes place, the sleeve 9 is also moved outward with the chisel shank, and by the flanges 10 and 11 on the sleeves 3 and 9 and the interposed cushion means 12, the outward movement of the parts is retarded and shooting of the sleeve 9 out of the barrel is prevented. Thus, the parts cannot be shot out of the barrel, either when the tool is operated while removed from the work or when the chisel glances off of the work during the operation of the tool and when the rivet head breaks off. This provides a safety feature and allows the operator to cut off heads of rivets without fear of the chisel being shot out of the barrel when the chisel glances off and when the rivet head is cut off. This saves time for the operator and enables more work to be done in a given space of time, as he does not have to be concerned with keeping the chisel in the barrel.

The plugs 15 having their outer ends curved, as stated, permit turning the chisel on its axis to comply with the surface of the work, as the sleeve 9 will turn freely in the tool nozzle except when its endwise movement is checked.

Moreover, by the construction described, an ordinary pneumatic riveting hammer as handled by one man may be used with a comparatively light chisel for cutting off the heads of rivets. Such riveting hammer with its quick stroke and automatic hammer piston has sufficient power for this work when a comparatively light chisel is employed as not enough of the blow of the hammer piston is transferred to the barrel of the tool to make the tool when put to this use, inefficient, as heretofore with a comparatively heavy chisel fitted in the barrel of the hammer.

While I have shown and described herein in detail a chisel retainer of my invention, it is of course to be understood that the details of construction and arrangement of parts illustrated may be variously changed and modified without departing from the spirit and scope of my invention.

I claim as my invention:

1. The combination with the barrel of a percussive tool, of a chisel having its shank supported in said barrel for relative longitudinal movements, and means associated with the barrel for retaining the chisel shank in operating position in the barrel comprising means for initially braking the outward longitudinal movement of the shank, said latter means comprising a sleeve disposed intermediate the barrel and shank, a braking element carried by the sleeve and engageable with the barrel and shank, and a cushion

for receiving the impact of said sleeve subsequent to the initial retardation of the outward movement of said shank.

2. The combination with the barrel of a percussive tool, of a chisel retainer comprising inner and outer sleeves mounted on the end of the barrel, the outer sleeve being fixed against longitudinal movement relative to the barrel and the inner sleeve being mounted for longitudinal movements relative to the barrel, a chisel having its shank mounted within the inner sleeve for longitudinal movements relative thereto, means carried by the inner sleeve and actuated by the chisel shank as the latter approaches its limit of longitudinal movement relative to said inner sleeve for connecting said shank and sleeve whereby they will continue outward longitudinal movement in unison, said connecting means cooperating with the barrel to gradually retard further outward movement of the sleeve and shank, and a cushion interposed between said sleeve to receive the impact of the inner sleeve subsequent to the initial retardation of the outward movement of said shank.

3. The combination with the barrel of a percussive tool, of a chisel having its shank inserted in said barrel, and a retainer carried by the barrel for supporting and retaining the shank therein for relative longitudinal movements, said retainer including braking and cushion elements acting in the order named to prevent the shank from being shot out of said barrel by the piston therein, said braking elements being interposed between the shank and the barrel and being forced into frictional engagement with the bore of the barrel by the shank in the outward movement of the shank to retard the same.

4. The combination with the barrel of a percussive tool, of a chisel having its shank inserted in said barrel, and a retainer carried by said barrel for supporting and retaining the shank therein for limited longitudinal movements, said retainer including braking and cushion elements acting in the order named to prevent the shank from being shot out of the barrel by the piston therein, said braking elements being interposed between the shank and the barrel, and inclined means on the shank to force the braking elements into frictional engagement with the bore of the barrel in the outward movement of the shank to retard the same.

5. The combination with the barrel of a percussive tool, of a sleeve slidably mounted in said barrel, a chisel having a shank inserted in said sleeve and projecting beyond the inner end thereof, braking elements retained by said sleeve between the shank and the barrel and engaging both of the same, inclined means on the shank for forcing the braking elements into frictional engagement with the bore of the barrel in the outward

movement of the shank to retard the same, and means to check the outward movement of the sleeve with said shank.

6. The combination with the barrel of a percussive tool, of a chisel retainer, comprising a sleeve inserted in the forward end of said barrel, a chisel having a shank inserted in said sleeve and projecting beyond the inner end thereof, said shank being provided with longitudinal grooves having inclined ends, plugs carried by said sleeve and engaging in said grooves, said plugs being held against movement out of said grooves by said barrel, and means associated with said barrel for holding said sleeve therein.

7. The combination with the barrel of a percussive tool, of a chisel retainer, comprising a sleeve inserted in the forward end of said barrel, a chisel, having a shank inserted in said sleeve and projecting beyond the inner end thereof, said shank being provided with longitudinal concave grooves with inclined ends, plugs carried by said sleeve and having rounded inner ends fitting in said grooves, said plugs being held against movement out of said grooves by said barrel, a retainer sleeve applied about the forward end of said barrel and projecting beyond the same, means for holding said retainer sleeve on said barrel, and means for holding said chisel sleeve in said barrel, consisting of flanges on said sleeves and cushion means between said flanges and carried by one of said sleeves.

8. The combination with the barrel of a percussive tool, of a chisel retainer, comprising a sleeve inserted in the forward end of the barrel and having a plurality of transverse holes therein, a chisel having a shank inserted in said sleeve and projecting beyond the inner end thereof, said shank having a plurality of longitudinal concave grooves with inclined ends, plugs in said holes and having rounded inner ends fitting in said grooves, the outer ends of said plugs engaging the non-yielding portion of the barrel surrounding said sleeve, a retainer sleeve applied about the forward end of said barrel and projecting beyond the same, and means for holding said chisel sleeve in said barrel, consisting of flanges on said sleeves and a cushion means between said flanges and carried by one of said sleeves.

9. The combination with the barrel of a percussive tool, of a chisel retainer, comprising a sleeve inserted in the forward end of the barrel and having a plurality of transverse holes therein, a chisel having a shank inserted in said sleeve and projecting beyond the inner end thereof, said shank having a plurality of longitudinal concave grooves with inclined ends, plugs in said holes and having rounded inner ends fitting in said grooves, the outer ends of said plugs

engaging the non-yielding portion of the said flanges and carried by one of said barrel surrounding said sleeve and being sleeves. In testimony that I claim the foregoing 10 curved on a radius approximating that of the bore of said barrel, a retainer sleeve as my invention, I affix my signature this 5 applied about the forward end of said barrel and projecting beyond the same, flanges 7th day of February, A. D. 1922.
